Mass., a corporation of Massachusetts

Application September 17, 1948, Serial No. 49,691

2 Claims. (Cl. 139—159)

1

This invention relates to a loom picker:

The object of the invention is to provide a novel and improved loom picker, and more particularly loom picker head of the loop type, which is constructed in such manner as to insure the maintenance of a snug and tight fit between the loop of the picker head and the picker stick when the picker head is subjected to use over long periods of time.

With this general object in view, and such others as may hereinafter appear, the invention consists in the loom picker head and in the various structures, arrangements and combinations of parts hereinafter described and particularly defined in the claims at the end of this specification.

In the drawings, illustrating the preferred embodiments of the invention, Figs. 1 and 2 illustrate in side elevation two modified forms of the present picker head mounted upon the usual picker stick; Fig. 3 is a plan view of the picker head shown in Fig. 1; Fig. 4 is a plan view of the picker head shown in Fig. 2; Fig. 5 is a perspective view illustrating an assembly useful in producing the picker heads shown in Figs. 1 to 4; and Fig. 6 is a plan view of a modified form of picker head embodying the invention.

Prior to the present invention considerable difficulty has been experienced with prior constructions of picker heads of the loop type, because of the tendency of the picker heads to work loose on the picker stick during the operation of the loom. Heretofore, it has always been considered that the looseness which has developed in this manner has been due to the stretching and elongation of the leather straps forming the loop, which extends around and embraces the picker stick. The effect of the looseness is a serious one, because of the fact that the picker head is distorted from its true position so that during the operation of the loom it will not follow a predetermined path of movement, and, as a result, defective picking of the shuttle occurs, and this results in thread breakage, as well as the production of defective grains of cloth. In addition, because of the fact that the picker head is distorted from a true operating position the face of the head is subject to engagement with the point of the shuttle at various angles, and as a result the picker head itself is subjected to excessive wear, and the life thereof becomes relatively short.

In studying the problem, I have found that the development of the looseness between the loop of the picker head and the picker stick, which has been experienced with prior types of picker heads

of the loop type after having been used for extended periods of time, while in a slight degree resulting from elongation of the loop itself, nevertheless appears to result principally from the enlargement of the loop caused by compression of the impact member of the picker head. In some instances, I have found that prior constructions of picker heads embodying compressible impact members resulted in a compression of the impact member in a direction longitudinally of the picker head, in very substantial amounts even up to $\frac{1}{16}$ of an inch. It is therefore apparent that the compression of the impact member enlarges the longitudinal dimension of the space within the loop by an amount equal to the compression of the impact member in such direction.

As a result of research and study of this problem, I have developed various forms of picker heads of the loop type embodying a construction of impact member which is designed to reduce to a minimum the longitudinal compression thereof during the operation of the loom. Accordingly, in one embodiment of the invention, I prefer to utilize an impact member made up of a plurality of individual pieces of rawhide, preferably cemented together into block form and mounted within an embracing leather strap loop in such manner as to present the end surface of the rawhide members to the thrust of the picker stick and to the impact of the point of the shuttle with the face of the picker head. The embracing straps forming the loop may, and preferably will embody an end portion of rawhide, which is preferably of a length and is disposed to extend around the two sides and across the face of the impact member and to be wound to form a multi-ply loop structure. The impact member and the embracing plies of the loop are preferably securely riveted together, and while the usual two rivets may be employed, I have experienced additionally good results utilizing three rivets, as will be described.

In another modification of the invention, I may prefer to form the impact member rolling a strip of rawhide and then compressing the same into substantially rectangular form as will be described.

Referring now to the drawing, 10 represents a picker head of the loop type which is mounted upon the usual picker stick 12 with the loop forming a space 14 of a size to permit the loop to be readily slipped over the head or upper end of the picker stick 12, and to tightly embrace the picker stick with the front face 15 of the picker stick

in engagement with the rear face 16 of an impact member 17 and with the rear surface of the picker stick in engagement with the inner face 19 of the back of the loop of the picker head.

In constructing the picker head, I prefer to produce the impact member 17, of an assembly of superimposed pieces of rawhide, which may be cut from a sheet of rawhide into rectangular form of the desired size. These individual pieces of rawhide may be and preferably will be cemented and pressed together into block form and then cemented on to the end surface of a composite strap 20 as shown in Fig. 5. This strap is provided with an end piece 22 of rawhide to which the rawhide impact assembly 17 is cemented. The under-surface of the end of the strap 22, is tapered at 24 as shown in Fig. 5 and the second end of the rawhide strap 22 is tapered as at 26 and cemented to the complimentary tapered end of a leather strap 28. With this construction, it is possible to wind the composite strap 20 about a mandrel so as to form the picker head shown in Figs. 3 and 4 with the rawhide strap 22 extending around and in contact with the two sides of the impact member 17 and across the front face thereof. The leather portion 28 of the composite strap is then wound around the mandrel to form a multi-ply loop such as is shown in Figs. 3 and 4 and to provide a triple-ply structure across the face of the impact member 17. The component parts of the picker head thus described may, and preferably will be united under pressure and with the use of suitable cement so as to form a strong, durable and wear-resisting structure.

As shown in Fig. 1, I may prefer to secure several plies of the loop structure to the impact member by means of two rivets 30 arranged in substantially vertical alignment and extending transversely through the impact member of the picker head substantially the center line thereof. As illustrated in Fig. 2, three rivets, 32, may be arranged to extend transversely through the multi-ply loop and picker head, two of the rivets being preferably arranged in substantially vertical alignment disposed slightly forward of the center line of the impact member, while the third rivet is extended through the rear portion of the impact member and in a position as illustrated in Fig. 2, disposed slightly above the longitudinal center line of the picker head. The effect of the three rivets is to materially stiffen the structure of the impact member and to assist in preventing compression thereof under the severe strains to which it is subjected during use, both in checking the shuttle and in throwing the same.

As illustrated in Fig. 6, I may prefer to form the impact member 17 of rawhide in one continuous strap rolled up into a tightly rolled condition preferably with the three plies cemented together and pressed into substantially rectangular form such as is illustrated in Fig. 5, but wherein the rawhide end will be of such length as to permit it to be rolled to form the impact member shown in Fig. 6, of the desired size and shape.

From the foregoing description of the several

embodiments of the invention, it will be apparent that the rawhide impact member, particularly of the multi-layered structure mounted to dispose the layers in such relation with respect to the blows of the picker stick, substantially reduces the liability of excessive compression of the impact member. This construction coupled with the three rivet structure insures a minimum of compression of the impact member and the results of extensive testing has demonstrated the ability of the present constructions of picker head to remain in tightly fitting relation upon the picker stick even after exceedingly long periods of constant use.

Having thus described the invention, what is claimed is:

1. A loom picker head comprising an impact member and a multi-ply loop structure within which the impact member is secured and through which the picker head is secured to the picker stick, said impact member being of a construction to minimize compression thereof under the impact of the shuttle, said impact member consisting of a laminated block with the laminations disposed longitudinally of the picker head made up entirely of a plurality of rawhide pieces assembled in side by side relation, said loop structure comprising a composite strap of durable fibrous material having a rawhide portion and a longer leather portion, said composite strap being wound about the impact member to form a double-ply loop portion and a triple-ply portion, the latter including the rawhide portion of said strap, said rawhide portion surrounding two sides and the front face of the impact member, said impact member extending the full width of the loop portion of the picker head, and a plurality of rivets extending through the triple-ply portion of the loop structure and transversely through the impact member.

2. A loom picker head as defined in claim 1 wherein three rivets are provided transversely extending through the triple-ply portion of the loop structure and through the impact member, one the rivets being extended through the rear portion of the impact member at substantially the center line of the picker head.
